UNITED STATES PATENT OFFICE.

THEODORE J. NELSON, OF CHICAGO, ILLINOIS.

DESIGN FOR A LIGHTING FIXTURE.

60,875.

Specification for Design.

Patented Apr. 18, 1922.

Application filed July 30, 1921. Serial No. 488,704. Term of patent 14 years.

To all whom it may concern:

Be it known that I, THEODORE J. NELSON, a subject of the King of Sweden, residing at Chicago, in the county of Cook and State of Illinois, have invented a new, original, and ornamental Design for a Lighting Fixture, of which the following is a specification, reference being had to the accompanying drawing, forming part thereof.

The figure is a perspective view of a lighting fixture, showing my new design.

The design comprises a small base and offset socket connected by a flexible strap to a counterweight as shown, said parts being constructed and assembled to afford a symmetrical and ornamental appearance.

I claim:

The ornamental design for a lighting fixture, as shown and described.

THEODORE J. NELSON.
